UNITED STATES PATENT OFFICE.

JOHN C. GOULD, OF CHICAGO, ILLINOIS.

DESIGN FOR A FRAME FOR ANIMAL-TRAPS.

SPECIFICATION forming part of Design No. 16,342, dated October 20, 1885.

Application filed August 7, 1885. Serial No. 173,871. Term of patent 14 years.

To all whom it may concern:

Be it known that I, JOHN C. GOULD, a citizen of the United States, residing at Chicago, in the county of Cook and State of Illinois, have invented a new and original Design for Frames for Animal-Traps, of which the following is a specification.

My design relates to animal-traps.

It consists in the design for the frame of such traps, hereinafter particularly set forth.

The drawing illustrates my design in perspective, the top being in the open or raised position.

In said drawing, A represents the body-frame, and B the cover or top. Both are given the general form and contour of a horseshoe, as plainly shown in the drawing, so that whether open or closed this feature of the design is very marked.

To make the representation more accurate, 20 the feet a a' a" may be located upon the body-frame in position similar to those occupied by the toe and heel calks, respectively, in the ordinary horseshoe.

I am aware that traps of this class have 25 been made with rounded or circular fronts and straight sides, and disclaim that shape.

I claim—

The design for the frame of an animal-trap, consisting of a frame having the conventional 30 shape or configuration of a horseshoe, as shown and described.

JOHN C. GOULD.
